Primary Examiner — Karen E Eldridge Powers*Assistant Examiner* — Margaret Leah Bryan(74) Attorney, Agent, or Firm — ScienBiziP, P.C.(57) CLAIM

The ornamental design for a lipstick tube as shown and described.

DESCRIPTION

FIG. 1 is a front, right and top perspective view of a lipstick tube, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is an enlarged top plan view thereof.

FIG. 7 is an enlarged bottom plan view thereof; and,

The broken lines depict portions of the lipstick tube that form no part of the claimed design.

1 Claim, 8 Drawing Sheets
